Their Atty.

UNITED STATES PATENT OFFICE.

ALBERT H. SAXTON AND JOSEPH J. BACHMAYER, OF BLISSFIELD, MICHIGAN,
ASSIGNORS TO NATIONAL BUNDLE TYER COMPANY, OF BLISSFIELD, MICHIGAN, A CORPORATION OF MICHIGAN.

NEEDLE-RELEASE FOR BUNDLE-TYING MACHINES.

1,322,628.

Specification of Letters Patent. Patented Nov. 25, 1919.

Application filed January 30, 1919. Serial No. 274,137.

To all whom it may concern:

Be it known that we, ALBERT H. SAXTON and JOSEPH J. BACHMAYER, citizens of the United States, and residents of Blissfield, 5 in the county of Lenawee and State of Michigan, have invented a certain new and useful Needle - Release for Bundle - Tying Machines; and we do hereby declare the following to be a full, clear, and exact description of the invention, such as will enable others skilled in the art to which it appertains to make and use the same, reference being had to the accompanying drawings and to the characters of reference marked 10 thereon, which form a part of this specification.

This invention relates to bundle tying machines, and particularly to the needle operating means thereof.

20 The object of our invention is the provision of means in connection with the needle operating means of a machine of the class described which, when the needle, in its forward stroke, encounters a predetermined resistance, will permit the needle to stand at rest during the remainder of the forward needle stroke operating movement of the actuating means, and which will, upon the next needle returning action of the 25 operating means, assume its normal needle operating connection with the needle. This is important in not only preventing injury to bundles being tied, but also in preventing injury to the hand of the operator which 30 may be grasping the bundle during the forward stroke of the needle.

The invention is fully described in the following specification, and while, in its broader aspect, it is capable of embodiment 40 in numerous forms, a preferred embodiment thereof is illustrated in the accompanying drawings, in which—

Figure 1 is an elevation of a machine embodying the invention, and Figs. 2 and 3 45 are enlarged end details of the needle release embodying the invention, with the latter in broken inoperative position.

Referring to the drawings, 1 designates the frame of a machine embodying the invention, 2 the tying mechanism and 3 the needle thereof, which operate in a manner well understood in the art. A pulley 4, which 50 is driven from any suitable source of power,

as from a motor (not shown) mounted on the frame top, is carried by a frame stud 55 and has a sprocket-wheel 5 fixed to its hub and connected by a chain 6 to a sprocket-wheel 7 mounted within a housing 8 on a shaft which operates the tying mechanism 2.

The needle 3 is fixedly carried by a horizontal rock-shaft 9, suitably journaled in the frame 1, and which is provided at the end thereof adjacent to the pulley 4 with a fixed arm 10, which, when the needle is in its raised or inoperative position, projects 60 downwardly therefrom. A second or operating arm 11 projects loosely from the shaft 9 adjacent to the arm 10, and is adapted to lie for a portion of its length at the front side of said arm. The outer end of the arm 11 is connected by an operating link 12 to a crank or wrist pin on a side of the sprocket-wheel 7, being projected for that purpose through an opening in the housing 8, thus causing a rocking needle operating 65 movement to be imparted to the arm 11 through the link 12.

A spring catch finger 13 projects transversely from the arm 11 through a registering opening 14 in the fixed arm 10, and has an offset catch portion 15 intermediate its ends, which normally engages the outer side of the arm 10 at the edge of said opening and yieldingly retains the two arms in operating connection so that they may act together as a single arm to impart rocking movements to the shaft 9. Should the forward operating stroke of the needle 3 be opposed by an abnormal force of predetermined resistance upon a forward operating 70 movement of the arm 11, the catch portion of the catch finger 13 will be sprung from holding engagement with the outer side of the arm 10 and pass forward through the opening 14, thus permitting the arm 10, 75

rock-shaft 9 and needle 3 to stand at rest during the remainder of the forward stroke of the arm 11. The catch finger 13 is of sufficient length without its catch portion 15, to prevent a complete withdrawal of 80 the finger from the opening 14 upon a relative breaking movement of the arms 10 and 11, and serves to guide the catch portion 15 back to operative catch engagement with the arm 10 upon the next rearward stroke of the 85 arm 11, as is apparent. For this purpose 90

the portion of the catch finger, without the catch portion 15, is preferably formed in an upward curve.

We wish it understood that our invention is not limited to any specific construction, arrangement or form of the parts as it is capable of numerous modifications without departing from the spirit of the invention as defined in the claims.

10 Having thus described our invention, what we claim as new, and desire to secure by Letters Patent, is—

1. In a machine of the class described, the combination with the needle operating 15 rock-shaft, of means for imparting rocking movements to said shaft, said means including a sectional arm, the parts of which are adapted to have relative movements to permit the rock-shaft to stand at rest during 20 an operating action of said means when a predetermined resistance is offered to a rocking of the shaft in one direction.

2. In a machine of the class described, the combination with a rock-shaft, a fixed 25 arm and a loose arm projecting from said shaft, a spring connection between said arms adapted to yield to permit the shaft to stand at rest when a predetermined resistance is offered to a rocking thereof by said connected arms, and means connected to said

loose arm for imparting rocking movements thereto.

3. In a machine of the class described, a rock-shaft, a loose arm and a fixed arm projecting from said shaft in adjacent relation, one having an opening therein, a spring catch member projecting through said opening from the other arm and yieldingly acting to retain the arms in operating relation, and means connected to the loose 40 arm for imparting rocking movements thereto.

4. In a machine of the class described, a rock-shaft, a loose arm and a fixed arm projecting from said shaft in adjacent relation, one of said arms having an opening therein, a spring-finger projecting from the other of said arms through said opening and having an offset catch portion adapted to engage the outer marginal edge wall of 50 said opening to yieldingly retain the arms in operating engagement and having an extension beyond said catch portion, and means connected to said loose arm for imparting rocking movements thereto.

In testimony whereof, we have hereunto signed our names to this specification.

ALBERT H. SAXTON.
JOSEPH J. BACHMAYER.
